UNITED STATES PATENT OFFICE

2,418,606

INVALID LIFT AND TRANSFER DEVICE

Ralph Nichol Smith, Los Angeles, Calif.

Application September 18, 1944, Serial No. 554,663

3 Claims. (Cl. 5—86)

1

This invention relates to hydraulic lifting devices, and more particularly to appliances for supporting, raising, transporting, transferring to other supporting means, and otherwise efficaciously servicing sick or injured persons.

A principal object of my invention is to furnish supporting means upon which a patient may be placed and removed therefrom with a minimum of movement, pain, and assistance, and when so supporting will allow exercise of the natural body functions of elimination in a sanitary and easily cleansable manner.

Other important objects of said invention are:

(1) To furnish means whereby said means may be easily and safely raised or lowered without noise or jar;

(2) To raise and lower parts or portions of the supporting means independently of the others;

(3) To provide supporting means upon which the patient may remain for long periods of time in maximum comfort;

(4) To provide means for moving patients to and from various parts of a hospital, and which will require little extra storage space when not in use;

(5) To furnish means for the support of various appliances used in the care and treatment of patients;

(6) To provide a simple unified control of the lifting means, thus leaving the attendant's hands free to attend patient or doctor.

Physical conditions of hospital patients vary greatly in their nature. In view of this, means for handling must of necessity be also variable, both in combination and separately in order to be of adequate service. For this vital reason my appliance is necessarily divided into parts or species, some of which may be used independently, or, when used in combination, form parts of the whole. It will be readily understood that any basic support for the attainment of the foregoing objects must be of very strong, rigid construction; while it is obvious that the primary means used for getting the patient upon the heavy base must be extremely light and easily adaptable to the bed position and condition of the body. It will also be seen that while the basic support must be of permanent construction and design, the attachments which it supports may be various and more or less temporary both in design and construction, in order to be adaptable to the case in hand.

With the foregoing and other objects in view, 55

2

reference is made to the accompanying drawings, in which:

Fig. 1 is a perspective view of a caster-mounted frame, the base of which is adapted to extend under a hospital bed and the vertical lifting members and laterally collapsible elements to sustain a torso or body-supporting panel or frame;

Fig. 2 is a plan view of the construction illustrated in Fig. 1, but showing in solid lines upper members of the frame in collapsed position, and in dotted lines such collapsible elements in extended position;

Fig. 3 is a plan view of a panel torso support with service opening;

Fig. 4 is a sectional view of end members of the frame as shown in Fig. 1 in bed-side position, the relative position of the bed being illustrated in dotted lines, and also depicting in dotted lines manipulation of the panel shown in Fig. 3;

Fig. 5 is a perspective view of hook-on panel extension for full length body support;

Fig. 6 is an end view in partial section of the frame in bed-side position, showing a modified form of crane arm and sling support;

Fig. 7 is a plan view of a modified form of body support;

Fig. 8 is a plan view of still another form of body support;

Fig. 9 is a sectional view of the body support taken on line 9—9 of Fig. 8;

Fig. 10 is a view in partial section of the hydraulic control valve and part of its manipulating means superimposed upon oil reservoir;

Fig. 11 is a sectional view of control valve taken on line 11—11 of Fig. 10, showing valve member 60 in center position, both control ports fully open.

Fig. 12 is a similar sectional view, showing valve member 60 fully closing entrance to pipe 49, entrance to pipe 48 being fully open;

Fig. 13 is a sectional view taken on line 13—13 of Fig. 11;

Fig. 14 is a perspective view of valve member 60.

Referring to the drawings in detail, the numerals of which indicate similar parts throughout the several views, and particularly for the moment to Fig. 1: Members of a base, comprising ends 15—15 and their longitudinal connecting member 16, are secured by any means well known in the art at contiguous ends adjacent to lower portions, respectively, of vertical tubular members 18—18, said base being supported on casters 19—19. Tubular members 18—18 are also held in ver-

tical spaced alignment by connecting bar 20, which is rigidly attached adjacent the respective upper ends of said tubular members 18.

Tubular rams 21 (for hydraulic lifting, as later described) slidingly telescope within the cylindrical bores of tubular members 18-18, respectively, the latter being closed in their lower ends to provide thereabove hydraulic lifting chambers 22-22 (Fig. 4).

Tubular rams 21-21 are each closed at their lower ends, which are provided with a suitable annular packing 23, well known in the art. Upper ends of vertical tubular members 18-18 are annularly enlarged to house ball bearings 24 so placed to prevent binding under load.

Ends of tubular rams 21-21 (Fig. 4) extend above upper ends of vertical tubular members 18-18, respectively; and hollow cylindrical fittings 25-25, preferably integral with corresponding ends of crane arms 26-26, rotatably telescope over said upper ends of tubular rams 21-21, T-handle set-screws 27-27 being screw-threaded in bores through cylindrical fittings 25-25, respectively, to permit optional locking of said crane arms 26-26 to said tubular rams 21-21, respectively, and stops 21a-21a (Fig. 4) are provided within tubular members 18-18 to limit downward movement of rams 21-21.

Crane arms 26-26 are each provided, equi-spaced from their respective vertically supported ends, with a preferably integral vertically bored lug 28, to each of which is loosely pivotally attached by a suitable pin (not numbered) an adjoining end of one of rods 29, the inner ends, respectively, of each of which rods 29, after passing through a concentric bore in the adjacent end of closure cap 30 of tube 31, telescope within tube 31. Each of extensions of rods 29 within tube 31 is provided with an annular stop 32 to prevent its retraction from telescoped relation, thus to limit extensibility of the assemblage of telescoping members 29-29 and 31-31. Inner ends of rods 29 seat respectively upon an adjoining end of one of helical springs 33-33, inner ends of said springs each being seated on an appropriate stop (not numbered) within said tube 31.

The outer side of right crane arm 26 is provided with a pair of spaced-apart slots 34-34, which slots each have a longitudinal extension (shown in dotted lines in Fig. 1) within said arms 26, said slots 34 functioning to receive hook-on members 35-35 for attachment and support, in an obvious manner, of a panel extension such as illustrated in Fig. 5 of the drawings, and which may be made of wood, light metal, plastic or any suitable material.

Outer ends (Figs. 1 and 2) of crane arms 26-26, respectively, are each provided with an arcuately outwardly extending vertically bored lug 36. Each of telescoping members 37-37 are bored to receive pivot pins 38-38 by which each of said members 37-37 are loosely pivoted to each, respectively, of lugs 36, thus forming semi-universal joints to allow the independent raising of either end of crane arm 26 with its attachments as desired without distortion or strain. Telescoping members 37-37 are slotted on their inner sides as required to allow the passage when closing of lugs 36-36.

Perspectively, the hydraulic lifting operating means are depicted in Fig. 1, details of construction thereof being illustrated in Figs. 6, 11, 12, 13 and 14, and will now be described.

Referring first to Fig. 1, which shows most clearly the complete assemblage: 39 indicates a

hydraulic fluid reservoir which is in communication through pipe 40 with the interior of pump cylinder 41, which cylinder contains a pump piston (which, being well known, need not be further described), the rod of which piston extends through an appropriate packing gland (not shown in detail) through the opposite end of pump-cylinder 41. Above said protruding end of said piston rod there is rigidly attached to an adjoining end of said pump cylinder 41 a bracket 42, the outer end of said bracket being bifurcated as shown at 43, between which bifurcations is pivoted, by an appropriate pin (not numbered), pedal bar 44. Below the point of pivoting of pedal bar 44, said bar 44 is provided with a downward extension (not numbered), to which is pivotally attached the protruding end of said pump piston rod. Pedal bar 44 is normally held in uppermost position by coil spring 45, its upper movement on release of the pedal retracting the pump piston.

Through the opposite end of pump cylinder 41 pipe-conduit 46 communicates with a valve chamber (later to be described) in valve housing 47 (details of valve operating means to be later described); and said chamber in said housing 47 communicates by pipe conduits 48 and 49 with respective hydraulic chambers 22-22 below rams 21-21 within vertical tubular members 18-18.

Still referring to the general assemblage of hydraulic lifting means shown in Fig. 1: Tubular valve stem 50 extends through a packing 50a and through housing cap 47a of the valve chamber (later described) and rotatably through an appropriate bore in member 20 of the supporting frame, to the upper end of which valve stem 50 is rigidly attached (by any well-known means) operating lever-handle 51, which latter is provided with spring means 52 (Fig. 10) well known in the art and not in detail illustrated, to resiliently engage in slots in arcuate member 53, the latter being carried on the upper surface of frame member 20. 54 (Figs. 10 and 13) is an operating pedal for relieving hydraulic pressure in hydraulic lifting chambers 22-22 to lower panel-supporting members of the frame.

In Figs. 10, 11, 12, 13, and 14 are illustrated details of valve mechanism within valve housing 47. In Figs. 10, 11, and 12 the pipe 46 from pump cylinder 41 into valve housing 47 is shown screw-threaded in a tapped bore in valve housing 47, which figures also illustrate conduit 55 which communicates with bored passage 56, ends of which latter register with pipe conduits 48 and 49, communicating with hydraulic chambers 22-22 below rams 21-21 in vertical tubular members 18-18.

Bored passage 56 (Figs. 11 and 12) is enlarged adjacent its ends to form compartments for ball check valves 57-57, each of which latter, respectively, is normally pressed upon its seat (closing its respective end of passage 56) by helical springs 58-58, which latter are, respectively, seated on one of annular rims 59-59. Valve member 60 (shown perspectively in Fig. 14) comprises a circular head 61 having extending downwardly from its periphery, and of the same outside radius as head 61, a flange 62 of uniform width, a segment of which flange is cut away as at 63 to provide a fluid passage. Concentric with head 61 of valve 60 extends upwardly tubular valve stem 50, which passes through a suitable packing 50a, and thence upward through

cap 41a of valve casing 41, as most clearly shown in Figs. 1, 10 and 13.

In Figs. 11 and 12 is illustrated the rotative movement of valve member 60 by which the cut-away portion 63 (shown most clearly in Fig. 14) of its segmental flange provides, partially or wholly, optional opening (controlled by the manipulating handle 51) for communication through pipe conduits 48 and 49, respectively, with the hydraulic chambers 22-22.

Referring particularly to Figs. 11, 12 and 13: Drain conduit 64 communicates at each of its ends 65-65, respectively, with bored passage 56, and, through port 66 (Fig. 13), communicates through pipe 67 with hydraulic fluid reservoir 39.

Within tubular valve stem 50 (as most clearly shown in Fig. 13) needle-valve 68 slidably fits, annular packing ring 69 around said needle-valve 68 permitting sliding movement of the valve, but preventing leakage of pressure fluid. Said needle-valve 68 is adapted to seat on the bevel (not numbered) around port 66. Pedal bar 70 is pivoted to lug 71 (Fig. 13), which latter is preferably integral with valve casing cap 41a. The inner end of pedal bar 70, which extends through an aperture 50b, as shown in Fig. 14, in tubular valve stem 50, is secured by link 72 to the upper end of needle-valve 68. Needle-valve 68 is normally held seated over port 66 by helical spring 73 within tubular valve stem 50, the lower end of spring 73 being seated on the upper side of the inner end of pedal bar 70, and the upper end of spring 73 being seated on a pin 74 which extends through an appropriate bore through walls of tubular valve stem 50 in which it is secured by any means well known in the art.

In Fig. 6 I have illustrated a supplemental frame and sling support in which 75 indicates a crane-arm, the lower end of which is rotatably telescoped into the upper end of ram 21, and which is vertically supported in telescoped relation on the upper end of ram 21 and upon fitting 25 by an annular flange 76. Obviously each of rams 21 as shown in Fig. 1 are provided with a like crane arm 75, so that upper ends of said crane arm 75 may swing to a position over the bed (indicated in dotted lines) or outward from the side of the bed.

Crane arms 75 are formed with hooks 77 adjacent their upper ends, from each of which hooks 77-77 is suspended a sling of heavy cord, the two reaches 78-78 of which are spaced apart by passing through slots or holes (not numbered) in the ends of spacing bar 79. Lower ends of each cord 78 has attached to it a hook 80 which is adapted to engage sides of a supporting panel (such, for instance, as illustrated in Figs. 7 or 8) the contour of the patient supported by the sling being indicated (Fig. 6) by dotted lines.

Figs. 3, 7 and 8 illustrate alternate forms of body-supporting panels, each designed as a special form of litter for the support of a patient, and each adapted while so supporting to be raised, lowered, transferred or transported on crane arms 26-26 and their appurtenances as shown in Fig. 1 of the drawings hereof, the specific forms of such body-supporting panels illustrated in Figs. 7 and 8 being particularly also designed for such manipulation by the crane-arm and sling support illustrated in Fig. 6 of the drawing.

In Fig. 3 is illustrated an approximately torso-length supporting panel comprising a rectangular strip 81 of sheet metal, plywood, plastic, or other suitable material having service opening 82 and 75

hand holes 83-83. Where, when using the torso-length support of Fig. 6, full length body support is desired for transportation or transference, the extension panel 84 illustrated in Fig. 5 is slipped under the patient's legs before raising, its hook-on members 35-35 being attached to crane arm 26 as heretofore described.

In Fig. 4 of the drawing a method of use of torso-supporting panel 81 (Fig. 3) is illustrated. Crane arms 26-26 with their connecting members being opened and lowered to rest upon the bed-mattress (the latter being shown in dotted lines), and the patient being rolled toward the opposite side of the bed, resting on his side at the edge of the frame supporting means, panel 81 is then placed in semi-vertical position (as shown in dotted lines in Fig. 4), its service opening approximating the patient, and the patient is then rolled onto panel 81 which is coincidentally lowered in the direction indicated by the arrows in said Fig. 4 until it rests upon crane arms 26-26.

The form of body support shown in Fig. 7 is designed for those patients who are badly injured and require raising and lowering with as little body disturbance as possible. In this form each of side members 85 and 86 of a long rectangular frame, preferably of metal tubing, are provided adjacent their respective ends with short lateral extensions 87 and 88, circular in cross section and adapted to telescope within corresponding ends, respectively, of end frame members 89 and 90. A sheet of fabric of any suitable material (such as canvas) of long rectangular form is cut to form spaced-apart strips 91-91, connected at outer ends by a continuous portion of the fabric which is wrapped around and sewed to frame member 86 by obvious means well known in the art. Adjacent each end corner of each of strips 91, shanks of spring hook members 92-92, (well known in the art, and which need not be further described) are secured, opposite ends being formed to hook over side member 85, the spring (not numbered) intervening the shank of the hook member serving to provide a longitudinal resilience of the hook member. The technique of the use of the body support shown in Fig. 7 is as follows: Side member 86, with its attached fabric strips 91 bunched, is placed at one side of the patient, and each strip 91 is separately slipped under the body of the patient and drawn snug. The frame end members 89 and 90 are then slipped beneath the patient and telescoped over lateral extensions 88 respectively. Said frame member 85 is now placed parallel with the hook-carrying ends of strips 91, and the hooks of members 92-92 are placed over side member 85, which is pulled outward to permit lateral extensions 87-87 to telescope within adjacent respective end members 89 and 90.

In Figs. 8 and 9 are shown another alternate form of body support in which the rigid tubular frame is divided into parts 93-94, which may be joined by socket members 99. Torso supporting frame 93 is crossed by rigid or semi-rigid band members 95-95 secured at their respective ends by any means well known in the art, as illustrated in dotted lines in plan in Fig. 8, a short slip-covered pad 96 of aerated latex or other resilient material being placed over and supported by said cross members 95. When full length support of the patient is desired, frame part 94 may be slipped into place as shown in Fig. 8, the legs of the patient being supported by the spaced-apart strips 97-97 of fabric, such as canvas or the like, ends of which carry members 98-98 adapted to

hook over each of the side members of frame 94, and which may be quickly removed or replaced without patient disturbance. The form of body support of Figs. 8 and 9 is designed to service a patient who, through spinal or other very grave injury, must remain upon it for relatively long periods of time with little or no change of body position.

The operation of the hydraulic lifting means is as follows: Assuming, first, that it is desired to raise rams 21-21 equally, operating handle 51 is placed in central position, thus moving valve member 60 in position shown in Fig. 11 with ingress of hydraulic fluid into pipes 48 and 49 fully open. The pump piston in cylinder 41 has been spaced a predetermined distance between the ends of cylinder 41 and with a conventional ball-check valve (not shown) closing pipe 40 from hydraulic fluid reservoir 39, pipes 48 and 49 of two respective hydraulic fluid lifting chambers and cylinder 41 on its reservoir side being filled with hydraulic fluid, a downward stroke of pedal 45 will force hydraulic fluid through pipe 46 and passage 56, unseating ball check valves 57, and then through the ends of passage 56 and through pipes 48 and 49 in equal quantities below each of rams 21, thus, the weight upon rams being equal, their upward movement will also be equal. Weight differential upon rams 21 may be readily compensated by partial closure of passage 56 to the lighter side by rotation of valve member 60; while the complete closing of passage 56, as shown in Fig. 12, at either end as desired makes the jack operation at the opposite end entirely independent regardless of the weight upon it, thus allowing either the head or feet of the patient to be raised or lowered at will. The spring means 45, heretofore described, after release of such depression of pedal 44 will return the pump piston to its initial position, and in doing so will pump a new charge of hydraulic fluid into the pump cylinder, the hydraulic fluid in the hydraulic lifting chambers and connecting conduits being prevented from returning to the pump cylinder by ball check valves (not shown, but well known in the art) within valve chamber 47. Such first depression of the pedal will raise the rams 21 a distance measured by the amount of fluid which has by the first pedal depression been forced beneath them. With each succeeding depression and release of pedal 45, an additional volume of pressure will be forced into the lifting chambers, further raising the rams 21-21. When, after having been equally raised, it is desired to equally lower each of rams 21 and the frame supported by them, the valve member 62 being in the position shown in Fig. 11, pedal 54 is depressed, opening needle valve 68 which permits (while the needle valve is off its seat) the fluid in the lifting chamber 22-22 below rams 21-21 and within pipe conduits 48

and 49 to flow back through drain conduit 64, through pipe 67, and into fluid reservoir 39. Obviously, release of pedal 54 will result in closing needle valve 68, and will stop the drain back to the fluid reservoir. If found desirable to lower one arm while holding the position of the other, valve member 62 may be moved by operating handle 51 to wholly or partially close the appropriate side of the drain line.

What I claim and desire to secure by Letters Patent is:

1. In a device of the character described, a base supported on casters, a plurality of vertically extending tubular members supported on said base, a plurality of crane arms, a plurality of members, each rotatably telescoping within one of said tubular members, and each rigidly attached at its upper end to an adjoining end of one of said crane arms, and means adjustably connecting a plurality of said crane arms to permit their relative movement in an arc with respect to their respective tubular members.

2. In a device of the character described, a hollow vertical standard, a hydraulic ram telescope within said standard, and a crane arm rigidly attached to an upper end of said ram and adapted to rotate with said ram in an arc with respect to said hollow vertical standard.

3. In a device of the character described, a base, a pair of tubular members supported on said base, a pair of rams, each respectively telescoped into one of said tubular members and rotatable with respect thereto, a pair of crane arms, each of said crane arms being rigidly attached to an upper end of one of said rams, means resiliently connecting said crane arms, and a body-supporting panel adapted to be supported on said crane arms.

R. NICHOL SMITH.
